FIG. 1 is a perspective view of a spray gun showing my new design;

FIG. 2 is a top plan view thereof;

FIG. 3 is a side elevational view thereof; and

FIG. 4 is a front elevational view thereof.

The characteristic feature of our invention resides in the particular configuration of the flared rear portion of the spray gun as shown in the several figures of the drawing.

We claim:

The ornamental design for a spray gun, substantially as shown and described.
